METHOD OF AND APPARATUS FOR PRODUCTION OF RAISED PATTERNS ON FABRICS

Karl Welti, Glasgow, Scotland

Application May 19, 1937, Serial No. 143,633
In Germany September 23, 1936

18 Claims. (Cl. 26—69)

The invention relates to the imparting of patterns to fabrics, more particularly webs of fabric, and refers to a method of producing raised patterns on fabrics and also to an apparatus for performing the method. The fundamental idea of the invention consists in imparting to the fabric raised patterns of a not entirely definite form, but causing the form of pattern once produced to be quite uniform as regards nature, 5 size and distribution over the entire web of fabric, so that the complete web of fabric will have imparted thereto a pattern which in every respect is uniform and equal throughout. According to the invention, this is accomplished in 10 particularly simple fashion substantially by the fact that the fabric, over a certain part of its path, is bunched together with merely slight possibility of yielding movement vertically to the path, and the small corrugations and folds thus 15 formed are caused permanently to retain their form by methods and means similar to an ironing operation.

For this purpose the fabric is pressed against a heating track and is conducted to the latter 20 at a speed which is greater than that at which it leaves the same, the pattern effect produced by the bunching together permanently retaining its form after leaving the heating track on account of a kind of ironing process. Owing to the fact 25 that both the rate of introduction as well as the rate of discharge may be exactly regulated it may be ensured that the formation of the corrugations takes place perfectly evenly, so that there 30 is also obtained the ensurty that if these differences are maintained the formation of the corrugations will be of a uniform nature as regards 35 form, size and distribution over the entire web. A carrier belt or backing may conveniently also be conducted together with the web of fabric 40 over the heating track, in such fashion, however, that in relation to the heating track it is situated towards the outside. Immediately after leaving 45 the heating track, however, separation is again performed between the fabric and the carrier belt, in order that the latter will not be able to impair the production of the pattern along the free path of movement. In order to enhance the 50 effect the fabric is preferably moistened before being conducted to the heating track, after the formation of the raised pattern along the heating track the subsequent treatment may take place along the usual lines, i. e., the fabric may be completely dried, or dyed or otherwise treated.

The method accordingly proceeds substantially 55 in such fashion that the fabric is conducted to

the heating track, for example with the aid of a conveying roller, at the end of which track there is performed by any suitable means a certain bunching together of the web of fabric which causes the corrugations to be produced 5 along the heating track. When the pattern has reached a certain measure of the heating track there will occur a pressure of material at the point of discharge, which ultimately is sufficient to overcome the bunching effect to such extent 10 that the patterned fabric leaves the heating track at a certain speed. This rate of discharge, however, must always remain smaller than the rate of introduction. At the same time a certain pressure may then be exerted by the bunching 15 device on the web of fabric leaving the heating track and having had corrugations imparted thereto by reason of the previous bunching action, in order in this way to impress the corrugations particularly effectively in the fabric. 20

Additional features of the invention are disclosed by the following description, the claims and the drawings.

For carrying out the method there may conveniently be employed the apparatus illustrated 25 by way of example in the drawings.

Fig. 1 shows a vertical longitudinal section through the apparatus according to the broken line I—I in Fig. 2, and

Fig. 2 is a vertical longitudinal section through 30 the apparatus according to the line II—II in Fig. 1.

In a frame 1 produced, for example, from sectional iron there is mounted to be rotatable on a transverse 2 with the aid of bearing jaws 3 a 35 heated drum or roller 4. This receives its drive from an electro-motor 5 (Fig. 2) by way of an intermediate gear 6, which sets into operation a chain 7 running over a sprocket wheel 8 of the drum 4. 40

In the frame 1 there is also mounted on a bracket 9 (Fig. 1) a lever 10 carrying a roller 11, which bears against the drum 4. This roller 11 is set into rotation at a certain speed by way of toothed gearing 12, 13 (the lever carrying the 45 roller 11 is naturally provided at both ends of the roller 11 in order to provide a better support).

On a bracket 14 on the opposite side of the machine there is mounted a second lever 15 carrying an additional roller 16, which likewise contacts with the periphery of the drum. This roller, however, is not driven, and its shaft 17, to which it is firmly secured, is extended beyond the frame and furnished there with a handwheel 18, so that the circumferential velocity of the roller 16, caused 55

by the rotation of the drum 4, may be reduced by releasing the handwheel to greater or smaller extent. In place of the handwheel there could also be furnished a brake capable of adjustment 5 for different braking effect on the shaft 17, and accordingly on the roller 16.

The two levers 10 and 15 carrying the rollers 11 and 16 are extended towards the centre. To the arms 19, 20 there are connected rods 21, 22 10 which, conducted downwards, terminate in turnbuckles 23, 24. The opposite ends of the turnbuckles are connected to levers 25, 26, which are mounted on the machine frame at 27, 28 and the free ends of which carry weights 29, 30, so that 15 by way of the turnbuckles 23, 24 and the rods 21, 22 the rollers 11 and 16 are pressed with a certain pressure against the drum 4 corresponding to the size of the weights.

As shown particularly clearly in Fig. 2, there 20 is provided outside of the machine frame on a vertical shaft 31 a handwheel 32, by the rotation of which there may be lifted to a greater or smaller extent a nut 34 which is mounted on the lever and furnished with the thread 33. The nut is 25 connected by way of a crank arm 35 with a shaft 36 mounted in the frame, so that upon rotation of the handwheel 32 the shaft 36 may be rocked accordingly. On the shaft 36, preferably at both ends, there are provided in engagement with the 30 double arrangement of the weighted levers 25, 26 crank arms 37 and 38, which are connected to rods 39 and 40 passing vertically upwards, which upon the rotation of the handwheel 32 may be lifted or lowered corresponding to the resulting 35 rocking movement of the shaft 36. These rods 39 and 40 are furnished with transversely projecting pins 41 and 42, which in the normal position according to Fig. 1 are situated just below the weighted levers 25 and 26. Upon the lifting of 40 the rods 39, 40 the levers 25 and 26 are accordingly raised by way of the transverse pins 41 and 42, so that at first the rollers 11 and 16 are relieved, while upon an additional lifting movement the rollers 11 and 16 are caused to be lifted completely clear from the drum 4.

On the upper transverse 43 of the machine frame a rod 46 is arranged to be adjustable in height by means of handwheels 44 and threaded spindles 45. On this rod there are mounted side 50 by side wires 47, which in Fig. 1 of the drawings are indicated by double-dotted and dash lines. These wires run from the rod 46 under the bearing shafts for the levers 10, between the roller 11 and the drum 4, under the bearing shaft for the 55 lever 15, and finally over guide rollers 48 to weights 49, which are suspended freely downwards, so that the wires are conducted with a certain tension over the periphery of the drum 4 dependent on the size of the weights. In this 60 connection it is desirable to furnish the rollers 11 and 16 with grooves (not shown) corresponding to the number of wires, so that these wires will not be pressed too strongly into the periphery of the drum 4.

Finally, there is also provided on the frame 65 an additional roller 50 over which, in the manner described later, there is conducted a carrier belt for the web of fabric to be treated, in such fashion that soon after the passage of the carrier belt 70 through the pass between the roller 16 and the drum 4 the carrier belt is separated from the web of fabric. This drum 50 is also preferably heated.

Finally, there is provided on the machine frame 75 on the side opposite to the drum 50 a bearing 51

for receiving the rolled web of fabric 52 to be treated, and preferably also a bearing 53 for a likewise rolled, carrier belt or carrier 54, in such fashion that this portion, or its bearing 53 respectively, is situated below the bearing 51 for the web of fabric, i. e., that this carrier belt 54 is located underneath the web of fabric on the drum 4.

The operation of this machine is as follows:—

The rolled web of fabric 52 is placed in the 10 bearing 51; a carrier belt 54 likewise rolled, for example a light muslin fabric or a fabric furnished with special weaving effects, is placed in the bearing 53. These two webs are applied to the periphery of the drum 4, in such a manner that there rests first on the periphery of the drum the carrier belt 54 and on the latter the web of fabric 52, and over these two layers there is then passed a carrier belt 57, which remains permanently in the machine. The rollers 11 20 and 16 are at this moment still lifted, for which purpose the handwheel 32 has previously been turned accordingly in order by way of the rods 39 and 40 and the transverse pins 41 and 42 to lift the weighted levers 25, 26, and accordingly 25 the rods 21, 22. In this way the wires 47 passing from the rod 41 over the periphery of the drum 4 are also released to such extent that the web of fabric with the two carrier belts can be properly applied. If necessary, the tension of 30 the wires must be reduced to such extent at this moment by the lifting of the weights 49 that proper application of the web is capable of being accomplished. When these preparations have been completed the handwheel 32 is turned until 35 the transverse pins 42 and 41 have fully released the weighted levers 25 and 26, so that these, through the medium of the rods 21, 22, now press the rollers 11 and 16 against the drum, or the webs of material on the drum. When now the 40 electro-motor 5 is set into operation there will be driven by way of the intermediate gear 6 the drum 4 and at the same time, by way of the intermediate gear 12, 13, also the roller 11. The roller 16 on the other hand is held by the 45 hand-wheel 18, so that a feed cannot take place at this point. On the other hand, proceeding from the roller 11, the webs, i. e., the lower carrier belt, the web of fabric and the upper carrier belt, are moved forwards corresponding to the 50 circumferential velocity of the roller 11. Since, however, they are unable to advance at the roller 16 there occurs along the path between the two rollers a bunching together by reason of which the webs are formed into corrugations, the size 55 of which depends on the extent of pressure of the wires situated thereover or on their distance from the drum 4. It is accordingly possible to produce larger or smaller corrugations by varying the size of the weights 49. Along the path 60 between the roller 11 and the roller 16 the moistened, bunched and corrugated web of fabric is pressed by the wires for a certain period against the hot drum. In this way there occurs a kind 65 of ironing operation, which fixes the corrugations. This ironing of the corrugations is also assisted by the outlet roller 16, which is capable of particularly pressing the moist warm corrugations.

When a certain length of the webs has been introduced by the roller 11 into the path leading to the roller 16, there will result at this roller 16 70 a certain pressure which will cause the braked roller 16 also to revolve, so that the web of fabric is then able to leave the track at this point. Usually the braking and release of the roller 16 75

will be performed by actuation of the handwheel by the workman supervising the running of the machine. Naturally the operation in question of the roller may also take place automatically or by mechanical control. By the breaking and release by means of the handwheel 18 the circumferential velocity of the roller 16 may be so regulated that in continuous operation the webs, corresponding to the desired corrugations, leave the track at a lower speed than that at which they are introduced into the same. After leaving they pass between the roller 16 and the drum 4 the upper conjointly moving portion 57 is quickly lifted from the fabric by the drum 50. Since the fabric was moistened before introduction into the machine, the carrier belt 57 will also have absorbed a certain amount of moisture. Owing to the fact, that the drum 50 is heated it can be ensured that the carrier belt is again rapidly dried. It is, however, also possible to employ other drying means. The carrier belt 57 is then conducted over a guide sheet 58, which is provided in the machine between the frame uprights 1, and finally over a tensioning device 59, and is then again passed to the drum together with the wires 47 under the shaft of the lever 10. The web of fabric 52 with the lower carrier belt 54 falls on the other hand on to a guide sheet 60, which is likewise mounted in the machine, and then collects in the lower trough 61 of this sheet, from where the fabric can be taken away.

Since the wires are permanently stationary they are naturally subjected to a certain wear by the webs of fabric continuously moving past. In order to provide compensation provision is made, by rotation of the handwheel 44, for a greater or smaller lifting or lowering of the threaded spindle 45, and accordingly of the rods 46, in order after a certain period of operation to move another portion of the wires into the range of the pressure or friction point.

It is preferable, and in numerous cases necessary, to provide a distending or stretching device 55 of a desired kind at the point of introduction of the webs of fabric, at least in conjunction with the web of fabric to be treated. A similar distending or stretching device 56 may, however, also be provided in conjunction with the lower carrier belt 54.

It may also be desirable to furnish the rollers 11 and 16 with elevations in order to impart merely partial feed or to hold back and press the web of fabric. In addition the rollers can be heated for the purpose of producing particular effects. To increase the pressure area there may also be furnished a plurality of rollers corresponding to the rollers 11 and 16, or there may be employed a cloth of rubber or the like placed over the two rollers for example similar to a conveying belt.

Other modifications are also readily conceivable within the scope of the invention.

Having now particularly described and ascertained the nature of my said invention and in what manner the same is to be performed, I declare that what I claim is:

1. In a method of producing raised patterns on fabric, the step which consists in positively feeding the fabric to a heated track at a speed which is greater than that at which the fabric is discharged from the said track by applying braking action against the fabric near the point of discharge by two cooperating rollers and imparting a lesser surface speed to one roller relative to the other roller so as to cause the fabric

to bunch together between the points of feed and discharge, and subjecting the fabric to an ironing operation when in the bunched condition.

2. In a method of producing raised patterns on fabric, the step which consists in positively feeding the fabric together with a carrier belt to a heated track at a speed which is greater than that at which the fabric is discharged from the said track by applying braking action against the fabric near the point of discharge by two cooperating rollers and imparting a lesser surface speed to one roller relative to the other roller so as to cause the fabric to bunch together between the points of feed and discharge, subjecting the fabric to an ironing operation when in the bunched condition, and causing the said carrier belt to separate from the fabric immediately after leaving the said heating track, the said carrier belt being situated on the side of the fabric away from the said heating track.

3. In a method of producing raised patterns on fabric, the step which consists in positively feeding the fabric between two carrier belts to a heated track at a speed which is greater than that at which the fabric is discharged from the said track by applying braking action against the fabric near the point of discharge so as to cause the fabric to bunch together between the points of feed and discharge, subjecting the fabric to an ironing operation when in the bunched condition, and causing the carrier belt situated on the side of the fabric away from the said heating track to separate from the fabric after leaving the track, the second carrier belt situated between the fabric and the heating track continuing to remain with the fabric after it leaves the said track.

4. A method of producing raised patterns on fabric, which consists in moistening the fabric, positively feeding the fabric to a heated track at a speed which is greater than that at which the fabric is discharged from the said track by applying braking action against the fabric near the point of discharge by two cooperating rollers and imparting a lesser surface speed to one roller relative to the other roller, so as to cause the fabric to bunch together between the points of feed and discharge, subjecting the fabric to an ironing operation when in the bunched condition, discharging the fabric from the said track, and thereupon treating the said fabric in any desired fashion.

5. In an apparatus for producing raised patterns on fabric, a heated revolving drum, a driven feed roller for the fabric bearing against the periphery of the said drum for positively feeding said fabric to the heated drum, and a discharge roller for the fabric bearing against the periphery of the said drum, said discharge roller having less surface speed than said drum.

6. In an apparatus for producing raised patterns on fabric, a heated revolving drum, a driven feed roller for the fabric bearing against the periphery of the said drum for positively feeding said fabric to the heated drum, and a non-driven discharge roller for the fabric bearing against the periphery of the said drum and having less surface speed than said drum.

7. In an apparatus for producing raised patterns on fabric, a heated revolving drum, a driven feed roller for the fabric bearing against the periphery of the said drum for positively feeding said fabric to the heated drum, a discharge roller for the fabric bearing against the periphery of the said drum and having less surface speed than said

drum, and means for imparting a desired braking action to the said discharge roller causing crumpling of the fabric.

8. In an apparatus for producing raised patterns on fabric, a heated revolving drum, a driven feed roller for the fabric bearing against the periphery of the said drum for positively feeding said fabric to the heated drum, a discharge roller for the fabric bearing against the periphery of the said drum, levers supporting the said rollers with the one end and mounted in the frame of the apparatus, and weights loading the said levers at their opposite ends.

9. In an apparatus for producing raised patterns on fabric, a heated revolving drum, a driven feed roller for the fabric bearing against the periphery of the said drum for positively feeding said fabric to the heated drum, a discharge roller for the fabric bearing against the periphery of the said drum, levers supporting the said rollers with the one end and directed towards the center of the apparatus, weights loading the said levers at their inwardly directed ends, and a connecting rod for lifting the said rollers away from the said drum.

10. In an apparatus for producing raised patterns on fabric, a heated revolving drum, a driven feed roller for the fabric bearing against the periphery of the said drum, a discharge roller for the fabric bearing against the periphery of the said drum in spaced relation relative to the said first roller to form a heating track for the fabric between the said rollers, means for pressing the said rollers against the said drum, at least one web adapted to accompany the fabric over the said heating track, wires disposed in the direction of movement of the fabric for pressing the said web against the said track, and means for lifting the said rollers from the said drum.

11. In an apparatus for producing raised patterns on fabric, a heated revolving drum, a driven feed roller for the fabric bearing against the periphery of the said drum, a discharge roller for the fabric bearing against the periphery of the said drum in spaced relation relative to the said first roller to form a heating track for the fabric between the said rollers, means for pressing the said rollers against the said drum, at least one web adapted to accompany the fabric over the said heating track, wires of variable tension disposed in the direction of movement of the fabric for pressing the said web against the said track, and means for lifting the said rollers from the said drum.

12. In an apparatus for producing raised patterns on fabric, a heated revolving drum, a driven feed roller for the fabric bearing against the periphery of the said drum, a discharge roller for the fabric bearing against the periphery of the said drum in spaced relation relative to the said first roller to form a heating track for the fabric between the said roller, means for pressing the said roller against the said drum, at least one web adapted to accompany the fabric over the said heating track, longitudinally adjustable wires disposed in the direction of movement of the fabric for pressing the said web against the said track, and means for lifting the said rollers from the said drum.

13. In an apparatus for producing raised patterns on fabric, a heated revolving drum, a driven feed roller for the fabric bearing against the periphery of the said drum, a discharge roller for the fabric bearing against the periphery of the said drum in spaced relation relative to the said

first roller to form a heating track for the fabric between the said rollers, means for pressing the said rollers against the said drum, at least one web adapted to accompany the fabric over the said heating track, wires disposed in the direction of movement of the fabric for pressing the said web against the said track, an adjustable rod to which the said wires are secured side by side at their one end, weights loading the said wires at their opposite ends, and means for lifting the said rollers from the said drum.

14. In an apparatus for producing raised patterns on fabric, a heated revolving drum, a driven grooved feed roller for the fabric bearing against the periphery of the said drum, a grooved discharge roller for the fabric bearing against the periphery of the said drum in spaced relation relative to the said first roller to form a heating track for the fabric between the said rollers, means for pressing the said rollers against the said drum, at least one web adapted to accompany the fabric over the said heating track, wires disposed in the direction of movement of the fabric and running in the grooves in the said feed and discharge rollers for pressing the said web against the said track, and means for lifting the said rollers from the said drum.

15. In an apparatus for producing raised patterns on fabric, a heated revolving drum, a driven feed roller for the fabric bearing against the periphery of the said drum, a discharge roller for the fabric bearing against the periphery of the said drum in spaced relation relative to the said first roller to form a heating track for the fabric between the said rollers, means for pressing the said rollers against the said drum, at least one web constructed as an endless belt and adapted to accompany the fabric over the said heating track, wires disposed in the direction of movement of the fabric for pressing the said web against the said track, the said web being disposed on the track between the said wires and the said fabric, and means for lifting the said rollers from the said drum.

16. In an apparatus for producing raised patterns on fabrics, a heated revolving drum, a driven feed roller for the fabric bearing against the periphery of the said drum, a discharge roller for the fabric bearing against the periphery of the said drum in spaced relation relative to the said first roller to form a heating track for the fabric between the said rollers, means for pressing the said rollers against the said drum, at least one web adapted to accompany the fabric over the said heating track and disposed on the side of the fabric away from the said heating track, a tensioning device for the said web situated in front of the said feed roller, a rapidly moving, preferably heated roller for the said web situated behind the said discharge roller, and means for lifting the said feed and discharge rollers from the said drum.

17. In an apparatus for producing raised patterns on fabric, a heated revolving drum, a driven feed roller for the fabric bearing against the periphery of the said drum for positively feeding said fabric to the heated drum, a discharge roller for the fabric bearing against the periphery of the said drum and having less surface speed than the drum, whereby the feeding of the fabric is greater than the speed at which the fabric is discharged by the said discharge roller, means for pressing the said rollers against said drum, and means for lifting said slower running roller from the said drum.

18. In an apparatus for producing raised patterns on fabric, a heated revolving drum, a driven feed roller for the fabric bearing against the periphery of the said drum for positively feeding said fabric to said heated drum, a discharge roller for the fabric bearing against the periphery of

the said drum and having less surface speed than the drum, and a stretching device for the fabric situated in front of the said feed roller.

KARL WELTI. 5
